UNITED STATES PATENT OFFICE.

EDWARD RADLOFF AND HENRY H. STOKES, OF CHICAGO, ILLINOIS, ASSIGNEES TO
CHICAGO MANUFACTURING COMPANY, OF CHICAGO, ILLINOIS, A COPARTNERSHIP
COMPOSED OF EDWARD RADLOFF AND HENRY H. STOKES.

AUTOMOBILE-RADIATOR.

1,368,197.

Specification of Letters Patent.

Patented Feb. 8, 1921.

Application filed October 6, 1917. Serial No. 195,016.

To all whom it may concern:

Be it known that we, EDWARD RADLOFF and HENRY H. STOKES, citizens of the United States, residing at Chicago, county 5 of Cook, State of Illinois, have invented a certain new and useful Improvement in Automobile-Radiators, and declare the following to be a full, clear, and exact description of the same, such as will enable others 10 skilled in the art to which it pertains to make and use the same, reference being had to the accompanying drawings, which form a part of this specification.

Our invention has for its object to produce an automobile radiator of novel construction which will insure a more efficient and rapid radiation of heat than has heretofore been possible and which shall not be 20 subject to injury by the freezing of water therein.

The various features of novelty whereby our invention is characterized will herein-after be pointed out with particularity in the claim; but, for a full understanding of 25 our invention and of its objects and advantages, reference may be had to the following detailed description taken in connection with the accompanying drawing, wherein:

Figure 1 is a front view of an automobile 30 radiator arranged in accordance with a preferred form of the present invention;

Fig. 2 is an enlarged vertical transverse 35 sectional view of a fragment of the cooling element;

Fig. 3 is a section taken at right angles to the plane of Fig. 2 at the side of and 40 parallel to one of the tubes;

Fig. 4 is a section taken approximately on line 4—4 of Fig. 3;

Fig. 5 is a perspective view of one of the 45 radiating vanes or fins; and

Fig. 6 is a side elevation of a fragment of one of the tubes of the radiator having a modified arrangement of vanes or fins.

Referring to the drawing, 1, 2, 3 and 4 represent respectively the top and bottom tanks or receptacles and side spacing members of any usual or suitable automobile 50 radiator. The heat interchanging element comprises a series of upright tubes, 5, having their ends extending through and soldered into plates, 6 and 7, which are secured to and form respectively the bottom of the member 1 and the top of the mem-

ber 2. It is common practice to make these 55 tubes cylindrical and surround them with vanes or fins square in outline. This is an inefficient arrangement and one that is apt to give trouble in cold weather due to the freezing of the water in the radiator and 60 ensuing bursting of the tubes. The reason for the inefficiency is that the distance of the water from the center of the cylindrical tubes to the exterior is quite long. In other words, the entire body of water in each of 65 the tubes is not brought close to the exposed cooling surface. Furthermore, the material of the square vanes or fins is not properly disposed to secure a maximum amount of radiation from the material 70 employed. It has also been proposed to arrange fins or webs in various other ways around cylindrical tubes in ways all of which are more or less objectionable.

In accordance with the present invention, 75 we make the heat interchanger tubes, 5, flat instead of round. This brings every portion of the water contained in the tubes quite close to a cooling surface. Furthermore, in case water freezes in the radiator, 80 the tubes will yield under pressure and instead of bursting, as the cylindrical tubes do, will assume more nearly spherical forms so as to increase their capacity and compensate for the expansion of the frozen 85 water. Each tube is surrounded by ribbon-like fins or vanes whose width is approximately equal to the smaller dimension of the tube. Thus a uniform radiating action is obtained in every direction radially of 90 each tube and a maximum efficiency results from the metal employed. Furthermore, in case one of the tubes freezes, the surrounding vanes or fins yield just as the tube does, changing their shapes without bursting 95 and without thus being destroyed. If the fins or vanes were made square, even though the tubes were flat, the vanes or fins would burst under an expansion of the tubes.

The vanes may conveniently consist of 100 small washer-like members, 8, each having the material at the center thereof struck up to form curved ears, 9 and 10, at the opposite ends of the long axis of the opening therein. The members 9 and 10 serve 105 as spacers between successive vanes or fins and, by being curved to fit the contour of the edges of the tubes will give the finished

product the appearance of a simple tube having vanes extending therefrom; no spacers being apparent to the eye.

If desired, the vanes or fins may be made 5 in the form of long strips, 11, spirally wound about the tubes as illustrated in Fig. 6.

While we have illustrated and described with particularity only a single form of our invention, with a single modification, we do 10 not desire to be limited to the exact structural details thus illustrated and described; but intend to cover all forms and arrangements which come within the terms employed in the definitions of our invention 15 constituting the appended claim.

We claim:

In an automobile radiator, a series of tubes shaped in cross section like long nar-

row rectangles having the short sides rounded, said tubes being so disposed that 20 the flat sides are at right angles to the plane of the front of the radiator, each tube having thereon a series of thin vanes provided with openings conforming to the contour of the exterior of the tube, and each vane having ears struck up therefrom at opposite ends of the elongated opening therein, the ears being shaped transversely to conform to the opposite narrow edges of the tubes 25 and serving as spacing devices between the 30 vanes.

In testimony whereof we sign this specification.

EDWARD RADLOFF.
HENRY H. STOKES.
